[57] **CLAIM**

The ornamental design for a combined handle and push-button housing for an electrically encoded push-button lock, as shown and described.

DESCRIPTION

FIG. 1 is an isometric view of a combined handle and push-button housing for electrically encoded push-button lock showing my new design it being understood that the broken lines are for illustrative purposes only to indicate a possible environment therefor;

FIG. 2 is an enlarged front elevational view thereof;
FIG. 3 is a front elevational view of FIG. 2 with an auxiliary power connection cover removed;

FIG. 4 is a cross sectional view thereof taken along line 4—4 in FIG. 2;

FIG. 5 is a cross sectional view thereof taken along line 5—5 in FIG. 2;

FIG. 6 is a top plan view of FIG. 2;

FIG. 7 is a bottom plan view of FIG. 2;

FIG. 8 is a rear elevational view of FIG. 2;

FIG. 9 is a right side elevational view of FIG. 2;

FIG. 10 is a left side elevational view of FIG. 2;

FIG. 11 is an enlarged isometric view of the auxiliary power connection cover;

FIG. 12 is a rear elevational view of FIG. 11;

FIG. 13 is a bottom plan view of FIG. 11;

FIG. 14 is a right side elevational view of FIG. 11; and

FIG. 15 is a top plan view of FIG. 11.
